[57] **CLAIM**

The ornamental design for an auxiliary output paper handler for a laser printer, as shown and described.

DESCRIPTION

FIG. 1 is a front, top and right side perspective view of the auxiliary output paper handler for a laser printer showing my new design, the broken line showing of a laser printer is environmental only and forms no part of the claimed design;

FIG. 2 is a front, top and left side perspective view of the auxiliary output paper handler for a laser printer with the output tray in an alternate position;

FIG. 3 is a right side elevational view of the auxiliary output paper handler for a laser printer;

FIG. 4 is a left side elevational view of the auxiliary output paper handler for a laser printer;

FIG. 5 is a left side elevational view of the auxiliary output paper handler for a laser printer with the output tray shown in an alternate position;

FIG. 6 is a top plan view of the auxiliary output paper handler for a laser printer;

FIG. 7 is a bottom plan view of the auxiliary output paper handler for a laser printer;

FIG. 8 is a front elevational view of the auxiliary output paper handler for a laser printer; and,

FIG. 9 is a rear elevational view of the auxiliary output paper handler for a laser printer.
